UNITED STATES PATENT OFFICE.

BENEDICT F. VOGT, OF LOUISVILLE, KENTUCKY.

WATER COOLER FOR REFRIGERATORS.

Application filed September 21, 1925. Serial No. 57,624.

This invention relates to refrigerators and has special reference to a water cooler for refrigerators.

One object of the invention is to improve 5 the general construction of devices of this character.

A second important object of the invention is to provide a one piece casting peculiarly adapted to constitute a water cool- 10 10 ing element and adapted to be inserted in the ice compartment of a refrigerator, the ice resting on top of the element.

A third object of the invention is to provide a device of this character of such con- 15 15 formation as to fit neatly in the ice compartment of a refrigerator while at the same time, being so arranged as to cause the water due to melting ice to flow in an established manner and drop into the drip pan 20 of the refrigerator, none of the water drip- 25 25 ping outside of said pan.

With the above and other objects in view as will be hereinafter apparent, the invention consists in general of certain novel de- 25 25 tails of construction and combinations of parts hereinafter fully described, illustrated in the accompanying drawings and specifi- 30 30 cally claimed.

In the accompanying drawings like char- 30 30 acters of reference indicate like parts in the several views, and;

Figure 1 is a perspective view of the de- 35 35 vice with a refrigerator shown therearound in dotted lines, the drip pan of the refrig- erator being shown in full lines.

Figure 2 is a cross section through the cooling unit and drip pan and showing the flow of the water drops.

The invention is intended to fit in the bot- 40 40 tom of an ice compartment of a refrigerator R and consists of a flat, horizontally dis- posed cell 10 having a top provided with an anti-clinally arranged upper surface 11 and lateral lugs 12 by means of which it is po- sitioned in the bottom of the ice compart- 45 45 ment over the drip pan P. Legs 13 hold the cell spaced above the drip pan and at two of the corners of the cell are positioned nip- 50 50 ples 14 and 15, the nipple 14 being the in- let nipple and communicating by a pipe 16 with a receptacle 17 arranged to receive the mouth and neck of a water bottle B. The nipple 15 communicates with a discharge cock being located at a lower level than the 55 55 receptacle 17.

On the under side of the cell is provided a pair of ribs 20 having opposed anticlinal undersurfaces 21 and abrupt shoulders 22.

In use the cell is located above the drip pan and the ice placed on top of the cell. 60 60 The water from the melting ice flows down the slight slope of the upper surface and, clinging to the surface of the cell, creeps around the lateral edges until it strikes the shoulders. It then flows down the shoulders, and drops into the drip pan, the surfaces 21 preventing its flow to the center. By means of this construction the collection of water between the ice and the cell is prevented and the ice rests at all times in close contact with 70 70 the top of the cell thereby obtaining the maximum cooling effect, while at the same time the water due to melting is retained in the drip pan and likewise adds to the cooling 75 75 of the refrigerator.

Meanwhile, water from the bottle has been thoroughly cooled and may be drawn off for drinking purposes.

There has thus been provided a simple and efficient device of the kind described and 80 80 for the purpose specified.

It is obvious that minor changes may be made in the form and construction of the invention without departing from the material spirit thereof. It is not, therefore, de- 85 85 sired to confine the invention to the exact form herein shown and described, but is desired to include all such as properly come within the scope claimed.

Having thus described the invention, 90 90 what is claimed as new, is:—

1. A water cooler element for refrigerators comprising a flat cell having its upper surface inclined downwardly towards each side from the middle and provided with 95 95 drip ribs on its under side.

2. A water cooler element for refrigerators comprising a flat cell having its upper surface inclined downwardly towards each side from the middle and provided with 100 100 drip ribs on its under side located parallel to the apical line of the top surface and laterally spaced therefrom.

3. A water cooler element for refrigerators comprising a flat cell having its upper surface inclined downwardly towards each side from the middle and provided with drip ribs on its under side located parallel to the apical line of the top surface and laterally spaced therefrom, the under surface 105 110

of the cell between said ribs being anticlinally arranged with respect to the median line of the cell.

4. A water cooler element for refrigerators comprising a flat cell having its upper surface inclined downwardly towards each side from the middle and provided with drip ribs on its under side, an inlet pipe connection at one corner of the cell, an outlet pipe connection at a second corner of said cell, and positioning lugs at the corners of said cell.

5. A water cooler element for refrigerators comprising a flat cell having its upper surface inclined downwardly towards each side from the middle and provided with drip ribs on its under side located parallel to the apical line of the top surface and laterally spaced therefrom, the under surface of the cell between said ribs being anticlinally arranged with respect to the median line of the cell, an inlet pipe connection at one corner of the cell, an outlet pipe connection at a second corner of said cell, and positioning lugs at the corners of said cell.

20 connected at one corner of the cell, an outlet

pipe connection at a second corner of said cell, and positioning lugs at the corners of said cell.

6. A water cooler element for refrigerators comprising a flat cell having its upper surface inclined downwardly towards each side from the middle and provided with drip ribs on its under side located parallel to the apical line of the top surface and laterally spaced therefrom, the under surface of the cell between said ribs being anticlinally arranged with respect to the median line of the cell, an inlet pipe connection at one corner of the cell, an outlet pipe connection at a second corner of said cell, and positioning lugs at the corners of said cell.

In testimony whereof I affix my signature.

BENEDICT F. VOGT.
